UNITED STATES PATENT OFFICE.

EDWARD L. MAAG, OF CLARKSBURG, OHIO.

MOLD.

No. 811,310.

Specification of Letters Patent.

Patented Jan. 30, 1906.

Application filed May 27, 1905. Serial No. 262,651.

To all whom it may concern:

Be it known that I, EDWARD L. MAAG, a citizen of the United States, residing at Clarksburg, in the county of Ross and State of Ohio, have invented certain new and useful Improvements in Molds, of which the following is a specification.

This invention comprises a novel construction of mold of that class designed particularly for forming sewerage-pipe.

The essential features of the invention reside in the peculiar construction of the mold-body, the special construction of collapsible core utilized therefor, and in the provision of a peculiar form of mold-ring, such as commonly used at the upper open end of molds of this type.

For a full description of the invention and the merits thereof and also to acquire a knowledge of the details of construction of the means for effecting the result reference is to be had to the following description and accompanying drawings, in which—

Figure 1 is a side elevation of a mold embodying the invention. Fig. 2 is a vertical sectional view. Fig. 3 is a horizontal sectional view on the line X X of Fig. 2. Fig. 4 is a detail perspective view of the mold-ring. Fig. 5 is a perspective view of the core. Fig. 6 is a detail perspective view of the mold-ring collapsed.

Corresponding and like parts are referred to in the following description and indicated in all the views of the drawings by the same reference characters.

Specifically describing the invention, the base of the mold is indicated at 1, and the same is formed upon its upper side with a base ring or annulus 2, preferably integral therewith. The ring 2 is designed to centralize the mold and core parts in setting the same up preparatory to the molding operation. The mold itself is indicated at 3 and is made in sections to facilitate removal of the mold from the molded article on completion of the molding operation, and the sections of the mold are adapted to abut or fit together in the customary way, being provided at their abutting portions with vertical ribs or flanges 4, adapted to be engaged by clamps 5, the latter firmly holding the mold parts above described together as the material is being tamped in the mold. The pipe or pipe-

sections which are formed by a mold embodying this invention are each molded with an enlarged end, in which a smaller end of a second adjacent section of the pipe is adapted to fit, and the construction of the mold-sections 3 is such as to form a peculiar swelled or enlarged end portion of the molded pipe-section, with advantages which will appear more fully hereinafter. The mold-sections 3 are adapted to fit about the ring 2 of the base 1 exterior of the latter, whereas the core 6 rests upon the base 1 within the ring 2.

The core 6 is collapsible and is composed of a plurality of pivotally or hingedly connected sections 6^a, 6^b, 6^c, and 6^d. It will be understood that the number of sections of the core 6, though preferably four, may be varied according to the desire of the manufacturer and the practical advantages of the construction. The sections 6^a and 6^d are not connected together directly, as are the other adjacent sections of the core, in order that the said sections 6^a in collapsing the core may be pulled inwardly, so that the several sections may be folded together to a certain extent in displacing the core from the mold. The meeting edge portions of the sections 6^a and 6^d are cut away on a bevel or inclination, so that such portions overlap, as shown at 7, when the core-sections are arranged in operative position. The section 6^a of the core has a strip 8 of metal or the like, attached thereto vertically of its inner side, said strip 8 being located adjacent the portion of the section 6^a, which abuts with the section 6^d, so that the strip will overlap the section 6^d upon the inner side thereof when the various sections of the core 6 have been spread apart and are arranged and held in operative position. The strip 8 is designed to preserve the cylindrical shape of the core to the greatest extent possible, so as to conduce to the formation of the perfectly cylindrical pipe-section upon completion of the molding operation. The core-sections may be held spread apart or in operative position by transverse braces 9, and these braces are perfectly elbow-braces, consisting of pivotally-connected sections, though it will be understood that any suitable form of brace means may be used to support and hold the core in operative position. The braces 9 may have pivotal connection with the sections 6^a and 6^d,

and said braces are adapted to break joint readily in order that the sections of the core may be collapsed in removing the same from the mold. It is preferable that at least a single brace be disposed near the upper and lower portions of the core, and in order to admit of readily collapsing the core-sections said sections may be provided with handles 10 upon the inner sides thereof, if desirable. 15 When the core 6 is in position in the mold 3, said core is of course spaced from the sections of the mold, and the material may thus be readily tamped in the space formed between the core and mold in a manner which will be evident to those versed in this art.

As before proposed, the upper portion of the mold is swelled or enlarged in order that the pipe-section formed thereby will have a corresponding enlarged end portion, for joint 20 purposes, and in the common construction of molds of the type to which my invention relates the upper extremities of the sections of the mold are usually formed with an outwardly-curving enlargement by which the 25 enlarged end of the pipe-section is made. The curved formation of this enlargement in the ordinary molds is such that the concrete or other material is often caused to crack at the point where the enlarged end portion of 30 the pipe-section joins the body thereof, for the reason that the material in the upper extremity of the mold cannot settle and thoroughly combine with the material below the enlarged portion of the mold. In the construction of the mold embodied in this invention, however, the upper enlarged end portion (indicated at 3^a) is formed by an upwardly and outwardly inclined extension 3^b, projecting from the body of the mold-sections, said 35 extension having a straight vertical flange 3^c projecting some distance above the top of the core 6. The extension 3^b is straight between the point at which it joins the body of the mold-sections and that point where said 40 extension joins the flange 3^c, and this construction is such that the material in the upper swelled or enlarged portion of the mold 3 is adapted to settle, and thereby thoroughly combine with that portion of the material between the body of the mold and the core 45 thereof, and this obviates all likelihood of breakage of the swelled or enlarged end of the molded pipe-section, as described hereinbefore with reference to the article molded by 50 the usual pipe-molds.

A mold-ring 11 is comprised also in this invention, and said ring is collapsible, being composed of sections 11^a, 11^b, 11^c, and 11^d, in general form somewhat similar to the sections of the core. The sections of the ring 11 are pivotally or hingedly connected also to the sections 11^a and 11^b, overlapping at the abutting portions, being disconnected at this point to permit collapsing of this ring in re-

moval thereof from the mold. The section 11^a is provided with a hasp-piece 12, having a slot to receive a staple 13, and a pin or wedge may be passed through the staple to secure the hasp-piece 12 thereto to hold the sections of the ring 11 in operative positions. 70 The ring 11 rests upon the upper end of the core 6, and in order to centralize said ring it is designed to provide each of the sections thereof with a downwardly-projecting extension 14, adapted to engage the inner side of 75 an adjacent section of the core 6 to hold the ring properly in position.

In using the invention the mold-sections and the core having been properly set up the material is disposed in the space between the mold and the core and tamped to the level of the upper extremity of said core, whereupon the ring 11 is then placed in position and the material tamped in the space between the ring and the flange 3^c, forming a part of the 85 upper enlarged end of the mold.

A feature of the invention resides in the provision of a jacket or shell 15 for the core 6, and said jacket or shell is made of light sheet metal and surrounds the core, so that 90 as the latter is collapsed and withdrawn from the mold the molded article is not likely to be injured thereby. The shell or jacket 15 can of course be readily removed and may be made in sections, or the same may be made 95 in a single piece of proper size to exactly fit about the core. The lower extremity of the jacket or shell 15 will of course be received in the ring 2, and when the shell or jacket 15 is withdrawn there is little or no likelihood that 100 the molded articles will suffer injuries therefrom. The shell or jacket 15 is primarily used in molding larger-sized pipe-sections and is dispensed with, though not necessarily, in molding smaller pipe-sections. 105

Having thus described the invention, what is claimed as new is—

1. In a pipe-mold, the combination of a mold composed of sections, a core therefor comprising a plurality of sections pivotally connected together, adjacent sections of the core having abutting portions disconnected to permit collapsing thereof, said disconnected portions of the sections overlapping, means for holding the sections in operative positions, and a strip carried by one of the sections disconnected as above described and adapted to overlap the adjacent abutting portion of the other disconnected section to preserve the cylindrical shape of the core. 110

2. In a pipe-mold, the combination of a mold composed of sections, a core therefor comprising a plurality of sections pivotally connected together, adjacent sections of the core having abutting portions disconnected to permit collapsing thereof, said disconnected portions of the sections overlapping, a strip carried by one of the sections discon- 115 120 125

nected as above described and adapted to overlap the adjacent abutting portion of the other disconnected section to preserve the cylindrical shape of the core, and joint-
5 braces interposed between opposing sections of the core.

3. In a pipe-mold, the combination of a removable core, and a jacket or shell surround-

ing the core and adapted to be reduced in diameter on removing the same.

In testimony whereof I affix my signature in presence of two witnesses.

EDWARD L. MAAG. [L. S.]
